UNITED STATES PATENT OFFICE.

LEON B. YEISER, OF OAKLAND, CALIFORNIA, AND ARTHUR I. FISCHER, OF CLEVELAND HEIGHTS, OHIO, ASSIGNORS TO GLAUBER BRASS MANUFACTURING COMPANY, OF CLEVELAND, OHIO, A FIRM.

WASHBASIN-FIXTURE.

1,333,826.

Specification of Letters Patent. Patented Mar. 16, 1920.

Application filed February 14, 1917. Serial No. 148,688.

To all whom it may concern:

Be it known that we, LEON B. YEISER, of Oakland, in the county of Alameda and State of California, and ARTHUR I. FISCHER, of Cleveland Heights, county of Cuyahoga, and State of Ohio, both citizens of the United States, have invented certain new and useful Improvements in Washbasin-Fixtures, of which the following is a specification.

10 This invention relates to improvements in wash basin and bath fittings, and comprises an organization of parts which include cold and hot water supply connections and a single centrally-disposed delivery spout affixed to a basin or bath tub having a discharge or exhaust pipe and a stopper or closure in the bottom thereof which is hand controlled by rod and lever means located at the rear and middle of the basin and with all 15 said parts so constructed and arranged that they are variously adaptable to basins and receptacles of different widths and sizes and other differences here and there which require adaptability in the fittings to install 20 the same therewith, all substantially as hereinafter fully described and more particularly pointed out in the claims.

In the accompanying drawings, Figure 1 is a plan view of a basin equipped with the 25 said fixtures. Fig. 2 is a vertical sectional elevation front to rear through the middle thereof.

Sheet 2, Fig. 3 is a sectional elevation on line 3—3, Fig. 1. Sheet 3, Fig. 4 is a side view of the valve and its stem and a section vertically through a supply tube and valve body. Fig. 5 is a sectional view of the spout and its fastening nut, and Fig. 6 a similar view of the delivery tube for the spout. Fig. 40 7 is a cross section in plan on line 7—7, Fig. 4.

The invention comprises separate supply pipes 2 through which hot and cold water is 45 separately supplied to two tubes 4 which are alike in construction and fixed at their top in the basin B through vertical holes therein, and tubes 4 have lateral delivery pipes 6 near their bottom which communicate with the branched delivery tube 7 and the single 50 delivery spout S open thereto at its upper end.

Nuts n engage each tube 4 on opposite sides of the basin B and fix said tubes on said basin, while corresponding nuts n' se-

cure the central tube member 7 in the same 55 manner to the basin. Each tube 4 has a valve seat in its bottom and a valve n seats thereon from above to govern the inflow or supply of water, and each valve has an internally-threaded extension b at its upper 60 end of hexagonal cross section operating in slideable engagement with the tube body under the action of a screw stem 5 projecting above the basin and provided with a handle g to rotate the same. A water tight closure 65 at the top of each tube 4 is provided by means of a collar c on each stem and a packing cup 8 resting on said collar and screwed into the upper end of the tube. The cup 70 contains packing and a follower nut 9 compresses the packing, while a cap or sleeve nut 10 enters the said follower nut 9 and has an annular flange engaged about the narrowed top of a rounded hollow cap and sleeve 12 75 resting on the basin and covering all the said parts except the handle.

The communicating pipes 6 are of substantially elbow shape and have sleeved or telescopic connection at both ends so that the 80 positions of the tubes 4 and 7 associated therewith may be accommodated to possible different widths of basins or spaces between the holes therein and to other possible conditions or positions in setting up or utilizing the parts involved. Slip nuts and packing 85 secure the ends of the pipes 6 in fluid-tight union with the threaded extension of each tube 4 and the curved branches of delivery tube 7, and a wide range of adjustment is obtained by their use in connection 90 with the several adjustments obtainable by nuts n and n', all of which is material to successful and practical adaptation of the fittings and fixtures to different and varying working conditions in different basins and 95 different relative locations of pipes and the like in a given installation.

In this way, the central bottom branched delivery tube 7 may have separate cold and hot water supply through separate pipes 6, 100 and I also provide this tube with a sleeve 14 in its center lengthwise, (Figs. 3 and 5) to accommodate a rod 15 through which a stopper 16 in the bottom of the basin is manipulated. The inflowing fluid runs in the annular space 17 between said sleeve and the surrounding wall of tube 7 and escapes at the top through openings 18 into the annular 105

space 19 in the head 20 of spout S, whence the fluid is discharged through said spout. The said head is made water tight to the exterior by an inner annular flange 21 thereon and a gasket 22 seating within the recessed top of nut n', and the top of the head is closed by a nut 23 and a ring gasket 24 when said nut is screwed onto the threaded extremity 25 of the tube 7. The nut 23 has a central opening through which rod 15 passes to the upper side of the basin.

Stopper 16 for the basin is operatively connected with the rod 15 by a line of mechanism best seen in Figs. 2 and 3 and comprising a short crank shaft 26 extending into a coupling 27 engaged on a tubular externally-threaded tubular connection 28 seated from above in the discharge of the basin and providing a seat at its top for said stopper and having an opening in its side communicating with the overflow 29 in the basin. Shaft 26 has a crank arm 30 fixed adjustably thereon at its outer end and is provided with a cam 31 at its inner end adapted to engage the head 37 on the bottom of the webbed extension 32 which carries and guides the stopper 16 in the connection 28. Opening and closing of the stopper 16 is effected by a slotted guide member 35 screwed upon the lower end of rod 15 and sliding in braced relation with shaft 26 opposite arm 30, which has its crank end slidably engaged with the lateral edge or slotted ear 37 of guide member 35.

The vertical elbow portion of pipe 6 may be raised or lowered and also rotated in making a connection with the downwardly curved branches of delivery tube 7, while the tubes 4 may be turned to project the lateral extensions for pipes 6 in any radial direction in making a connection, and the pipe 6 is also slideable in the extension, in this way facilitating adjustments to any given need.

What we claim is:

1. In a basin fitting as described, a water supply member having a valve seat therein,

a valve slidably mounted over said seat, a valve stem extending through the top of said member having a collar, a cup-shaped packing nut and packing therein seated on said collar and screwed into the top of said member, a follower nut screwed into said packing nut, an inclosing sleeve for said parts, and a tubular nut about said stem engaging the top of said sleeve and said follower nut.

2. A basin fitting, comprising a branched delivery tube having an exteriorly-threaded body and a reduced threaded upper extremity, a spout member and nuts sleeved upon said body, a cap nut engaging said threaded extremity and securing said member to said delivery tube, and packing between the joints of said parts.

3. A basin fitting, comprising a delivery tube having separate supply branches at its bottom and a threaded extension and side openings at its top, a clamping annulus for said tube having a packing seat in its upper face and packing in said seat, a spout member having a hollow body sleeved upon said tube and seated upon said packing, and a nut in the upper end of said spout body in screw engagement with said threaded extension.

4. A basin fitting, comprising a water delivery tube having separate supply branches and a central opening lengthwise therethrough and an annular water mixing chamber therein open to said branches, a pair of nuts in screw engagement with said tube adapted to secure the tube to a basin, a separate spout member detachably sleeved upon said delivery tube and having a recessed base inclosing one of said nuts, and a fastening nut for said spout member having a central passage adapted to register with the central opening in said delivery tube.

In testimony whereof we affix our signatures.

LEON B. YEISER.
ARTHUR I. FISCHER.
